DESIGN FOR A CASING FOR A CINEMATO- GRAPH

John Tuomey, New York, N. Y.

Application August 31, 1938, Serial No. 79,648

Term of patent 3½ years

To all whom it may concern:

Be it known that I, John Tuomey, a citizen of the United States, residing at 73-20 Austin Street, in the city of New York, county of Queens, State of New York, have invented a new, original, and ornamental Design for a Casing for a Cinematograph, of which the following is a specification, reference being had to the accompanying drawing, forming part thereof.

Figure 1 is a front perspective view of a casing for a cinematograph showing my new design.

Figure 2 is a side elevation of the same, showing the cover sections of the casing separated from the central body section.

The sides of the casing not shown are without ornament.

I claim:

The ornamental design for a casing for a cinematograph, as shown and described.

JOHN TUOMEY.
